UNITED STATES PATENT OFFICE.

MICHAEL KRANZ, OF CHICAGO, ILLINOIS, ASSIGNOR OF ONE-FOURTH TO WINAND H. NELLES, OF CHICAGO, ILLINOIS.

SWIVEL PLUG.

Application filed January 6, 1926. Serial No. 79,540.

My invention relates to a swivel plug, and an object of the invention is to provide such a plug including a body portion with a plurality of sockets and a swivel plug portion 5 rotatably connected to said body portion for attachment to the usual screw socket.

Other objects will appear hereinafter.

The invention consists in the combination and arrangements of parts hereinafter 10 described and claimed.

The invention will be best understood by reference to the accompanying drawings forming a part of this specification, and in which,

15 Fig. 1 is a plan view of the swivel plug; Fig. 2 is a side view thereof;

Fig. 3 is an end view;

Fig. 4 is an inner view of one of the body members or shells taken substantially along 20 line 4—4 of Fig. 5;

Fig. 5 is a longitudinal sectional view taken on line 5—5 of Fig. 1;

Fig. 6 is a cross sectional view taken on line 6—6 and Fig. 5; and

25 Fig. 7 is a plan view of the metallic member including the contact fingers.

The form of my invention illustrated in the drawings comprises a body part with a plurality of sockets, and a threaded plug 30 part which is swiveled or rotatably mounted on the body part, so as to be readily inserted and fastened in a threaded socket, and without rotating or turning the body part with its plurality of sockets adapted to have

35 a number of push plugs attached thereto. The body part or multiple socket part comprises a pair of outer members or shell members 10 which are substantially identical in construction and have a plurality of con-

40 nected or intersecting grooves or channels 11 provided in the opposing faces. A spacing member or intermediate member 12 is placed between the shell members, and screws or elements 13 are used to fasten members 10

45 and 12 together. A metallic member 14 is provided with a plurality of contact fingers or elements 15 which are arranged to rest in the grooves 11 and have curved or bent over outer ends 16 forming resilient con-

50 tact for receiving the contact stems or fingers of other push plugs. Stems or bars 17 and 18 are mounted on the pair of metallic members 14, and have their outer ends 17' and 18' bent over transversely of the

55 body member, the end 17' being spaced from

the shell member 10 and the end 18' being preferably bent over to engage the spacing member 12.

The threaded upper part or plug portion comprises a threaded collar 20 provided with an annular flange 21 which has its inner end 22 extending downwardly, and the free edge thereof bent outwardly to firmly engage a knurled operating member 23 and fasten it on collar 20, a ring 24 being provided on member 23 for a secure attachment to the collar 20. A neck 25 of insulating material is mounted on collar 20 and is provided with a cut-out portion or notch 26 to engage over bent end 17' of stem or bar 17 and to prevent the neck 25 from rotating on the body portion. A contact member or screw 27 extends through neck 25 and is fastened in the bent end 18' of stem or bar 18 thus retaining the neck firmly in position on the body part, 75 while the knurled member 23 and its attached collar 20 are rotated for mounting the device on a threaded socket.

It is apparent from the above disclosures that I have provided a convenient swivel 80 plug including a socket part adapted to receive a plurality of push plugs, and have arranged the threaded plug part for convenient attachment to a threaded socket, without the necessity of turning or rotat- 85 ing the body part with its sockets and the plurality of push plugs which may be attached thereto; and furthermore that the entire device is arranged so that it may be readily assembled and taken apart when de- 90 sired, and provides a very useful and economical construction.

While I have illustrated and described the preferred form of construction for carrying my invention into effect, this is capable of 95 variation and modification without departing from the spirit of the invention. I, therefore, do not wish to be limited to the precise details of construction set forth, but desire to avail myself of such variations and 100 modifications as come within the scope of the appended claims.

Having described my invention, what I claim as new and desire to secure by Letters Patent is:

1. A device of the class described comprising a body with a plurality of channels, metallic members with a plurality of contact fingers mounted in said channels to provide a plurality of electric sockets, contact bars 110

fastened to said metallic members and having their outer ends bent over, one end being spaced from said body, a collar with flange means for engaging under said bent end, 5 operating members mounted on said flange means and collar for rotating the collar, a neck in said collar and having a notch for engaging over said bent end, and a contact pin extending through said neck and engaging the other bar to retain the neck and collar in position on said body.

2. A device of the class described comprising a body with shell members having connected channels therein, a spaced member mounted between said shell members, metallic members with contact fingers mounted in said channels, contact bars extending from said metallic members, one of said bars having the end bent outward and 10 spaced from the body, the other having the end bent over and engaging the spacing member, a threaded collar with flange means

engaging under said outwardly bent end, means on said collar for rotating the same, a neck mounted in said collar, and a contact member extending through said neck and fastened on the other bent end which engages the spacing member.

3. A device of the character described comprising a body having a plurality of channels, a plurality of contacts arranged in the channels to provide a plurality of electric sockets, contact bars fastened to said contacts and having their outer ends bent over, a collar arranged above the body, a non-conducting neck received in said collar and provided with a recess receiving one of the bent ends whereby the neck is held against rotation, and an electrode passing centrally through the neck and engaged with the other bent end.

In testimony whereof I have signed my name to this specification.

MICHAEL KRANZ.
